UNITED STATES PATENT OFFICE.

ZACHARY T. FLOWERS, OF OLMSTEAD, KENTUCKY.

FIRE-SIGNAL.

SPECIFICATION forming part of Letters Patent No. 761,368, dated May 31, 1904.

Application filed May 8, 1903. Serial No. 156,255. (No model.)

To all whom it may concern:

Be it known that I, ZACHARY T. FLOWERS, a citizen of the United States; residing at Olmstead, in the county of Logan and State of Kentucky, have invented a new and useful Fire-Signal, of which the following is a specification.

This invention relates to fire-alarms; and the object in view is to provide a portable alarm capable of being applied at any convenient point about a residence, store, storehouse, or depot so as to give timely warning in case of fire.

Another object is to construct the alarm so that the detonating portion thereof will not become affected by atmospheric changes and also to provide against deterioration by other causes.

A further object of the invention is to provide the covering with a suitable protection against destruction by insects or vermin.

To these ends the invention consists in certain novel details of construction and advantages attained thereby, all of which will be hereinafter specifically set forth and claimed, reference being had to the accompanying drawings, illustrating the preferred embodiment of my invention, and in which—

Figure 1 is a view in elevation of the alarm complete. Fig. 2 is a vertical longitudinal sectional view through the alarm. Fig. 3 is a detail perspective view of the detonator and the covering therefor. Fig. 4 is a cross-sectional view through the alarm.

In carrying out the invention a suitable charge of a detonating compound is employed, with which is combined a fuse, the whole being entirely enveloped and protected by a covering of impervious material, which will prevent any deteriorating influences acting upon the fuse or the charge, owing to atmospheric changes.

In the preferred form, as illustrated by the drawings, 1 designates the detonating charge, preferably comprising a common fire-cracker having the usual fuse 2. In order to protect the cracker, a suitable covering 3 is provided, preferably consisting of corn-pith or similar fibrous and absorbent material, which constitutes an envelop entirely inclosing the fire-

cracker and the fuse. In applying the covering I prefer to split the stalk in the center and then remove a portion of the interior thereof to form pockets or seats 4 and 5, one in each member, of sufficient sizes to permit of the reception of a fire-cracker within, the fuse 2 lying between the flat end portions of the members. A cord or flexible securing medium 6 is securely wound around one end 7 of the pith and compresses the same, so that it will form a shoulder over one end of the detonating core. In order to fasten the sectional envelop or cover securely over the charge, the flexible binder 6 is wound around its exterior and is fastened to the opposite end 8 of the cover, which is compressed in a like manner as the end 7. The entire device is then coated with a suitable impervious compound or material, which will protect it against deterioration from atmospheric changes, as well as from the attacks of insects.

The absorbent properties of cornstalk-pith will cause the compound—such as oil, tar, &c.—to be taken up in sufficient quantity to preserve the cellulose and fibers thereof, and as the compound will be of a highly-inflammable character the covering or envelop will quickly burn off, releasing the alarm within, which will explode and indicate the presence of fire.

Owing to the inexpensive character of this device, it is contemplated to utilize numbers of these alarms within and without premises to be protected, and these will be disposed at the points in a room or building where fire is most likely to start or gain greatest headway.

The alarms can be suspended by the binding-cord, or suitable staple can be employed, if desired.

I claim—

1. In a fire-alarm, a detonator, and an envelop therefor, comprising two sections of fibrous material secured together so as to entirely cover the detonator and a waterproof coating over the envelop.
2. A detonating fire-alarm comprising an explosive incased in a shell with a fuse leading therefrom, an outer casing formed of two sections of compressible fibrous material having registering sockets to receive said shell,

said outer casing being coated with a water-proof and highly-inflammable material, and a binding member wrapped around said sections and drawn tightly around the ends thereof to 5 compress the outer casing at those points.

3. A detonating fire-alarm comprising an outer casing formed of two sections of fibrous material having registering sockets on their inner faces with reduced extensions leading 10 from said sockets and terminating short of the ends of said sections, an explosive disposed in said sockets with a fuse leading therefrom and

embedded in said reduced extensions of said sockets whereby the explosive and its fuse are entirely incased within said outer casing, said outer casing being coated with a waterproof and highly-inflammable material. 15

In testimony that I claim the foregoing as my own I have hereto affixed my signature in the presence of two witnesses.

ZACHARY T. FLOWERS.
